UNITED STATES PATENT OFFICE

LEONARD B. KRICK, OF CHICAGO, ILLINOIS, ASSIGNOR TO POPSICLE CORPORATION OF THE UNITED STATES, OF NEW YORK, N. Y., A CORPORATION OF DELAWARE

DESIGN FOR A CONFECTION

Application filed October 8, 1930. Serial No. 37,182. Term of patent 14 years.

To all whom it may concern:

Be it known that I, LEONARD B. KRICK, a citizen of the United States, and residing at Chicago, in the county of Cook and State of Illinois, have invented a new, original, and ornamental Design for a Confection, of which the following is a specification, reference being had to the accompanying drawings, forming part hereof.

Fig. 1 is a perspective view of a confection showing my new design.

Fig. 2 is a front elevational view thereof.

Fig. 3 is a side elevational view thereof.

Fig. 4 is a top plan view thereof.

I claim:

The ornamental design for a confection substantially as shown.

LEONARD B. KRICK.
